(57) **CLAIM**

The ornamental design for side lock wiper arm connector, as shown and described.

DESCRIPTION

FIG. 1 is an isometric view of the side lock wiper arm connector of the present invention;

FIG. 2 is a front elevational view of the wiper arm connector of FIG. 1;

FIG. 3 is rear elevational view of the wiper arm of FIG. 1;

FIG. 4 is a left side elevational view of the wiper arm connector of FIG. 1;

FIG. 5 is a right side elevational view of the wiper arm of FIG. 1;

FIG. 6 is a top plan view of the wiper arm connector of FIG. 1; and,

FIG. 7 is a bottom view of the wiper arm connector of FIG. 1;

1 Claim, 4 Drawing Sheets
